[57] CLAIM

The ornamental design for a control unit housing for a control panel mounted control station, as shown.

DESCRIPTION

FIG. 1 is a perspective view of the control unit housing for a control panel mounted control station as viewed from the right side showing the top and front side of the device;

FIG. 2 is a rear view of the FIG. 1 device.

The left and right side view of the FIG. 1 device are substantially identical as well as the top and bottom views of the device.

FIG. 1

FIG. 2
